UNITED STATES PATENT OFFICE.

VIRGIL C. FRANCIS, OF MINNEAPOLIS, MINNESOTA.

AUTOMATIC FILM-CHANGE ALARM AND ROTATING DEVICE.

Application filed June 27, 1921. Serial No. 480,546.

To all whom it may concern:

Be it known that I, VIRGIL C. FRANCIS, a citizen of the United States, residing at Minneapolis, in the county of Hennepin and State of Minnesota, have invented certain new and useful Improvements in Automatic Film-Change Alarm and Rotating Devices; and I do hereby declare the following to be a full, clear, and exact description of the invention, such as will enable others skilled in the art to which it appertains to make and use the same.

This invention relates to a moving picture machine and particularly to the operation of the film carrying member thereof. As is well known to those skilled in the art, modern motion picture places require the use of several films and if only one machine is being used, a film when run through must be replaced by another. In many theatres two machines now are used and when the film is paid out on one, the other machine is started. It has been the practice to run one film entirely through to the end before starting the other machine or taking any steps to replace the film. This results in a delay occurring between the portrayal of the two films.

It is an object of this invention, therefore, to provide a machine with an indicating means which will indicate to the operator when the film is nearing its end.

It is a further object of the invention to provide additional indicating means to indicate to the operator the time when the film is just about completed so that if an additional machine is used, the same can be started.

It is still a further object of the invention to provide means which will be operated by the same indicating means to turn on the light on the additional machine and start the same for operating on the next film.

These and other objects and advantages of the invention will more fully appear in the following description made in connection with the accompanying drawings in which like reference characters refer to the same parts throughout the different views and, in which—

Fig. 1 is a view in side elevation of a casing forming part of a moving picture machine and accompanied with applicant's invention, a portion thereof being shown in section;

Fig. 2 is a central vertical section of such casing in parts;

Fig. 3 is a horizontal section taken on line 3—3 of Fig. 2 looking in the direction 60 of the arrows and shown on an enlarged scale;

Fig. 4 is a view on an enlarged scale showing a portion of the invention;

Fig. 5 is a partial sectional view of the 65 device showing a modification; and

Fig. 6 is a view in elevation of the device shown in Fig. 5 as seen from the right thereof.

Fig. 7 is a diagram of a modified circuit. 70

Referring to the drawings, a casing 1 forming the casing of the film carrier or reel of a moving picture machine is shown, in which is mounted on suitably rotating shafts the film carrier or reel 2. This film 75 carrier or reel 2 comprises the hub portion 2^a and the disc portion 2^b. The film A is wound on the hub portion 2^a and paid out or unwound therefrom as the film is projected and passes out through opening 1^a in 80 the casing. The disc 2^b is spaced some distance from the rear wall 1^b of the casing and is equipped with a small spring arm 3 arranged radially thereon and riveted or otherwise rigidly secured to the disc at its 85 outer end. The arm 3 extends radially inwardly in contact with the disc and has one end bent substantially at a right angle to extend forwardly through an opening 90 formed in said disc, the end 3^a of the forwardly extending portion being again bent slightly upwardly. The layers on the film A are superposed on the hub 2^a as shown in Fig. 4 and the film is ordinarily provided along one edge with a series of apertures. The forwardly projecting portion of the member 3 as shown in Fig. 5 is disposed between the layers of the film A and the upwardly projecting portion 3^a thereof which is quite narrow enters one of the 100 apertures customarily formed in the edge of the film and by which it is moved. The member 3 is made of spring material and normally tends to assume the position shown in dotted lines in Fig. 4. Owing to the engagement of the portion 3^a, however, with the apertures in the film, member 3 is held under tension in the position shown in full lines in Figs. 1 and 4 until released by the film, when it will assume the position shown 105 in dotted lines in Fig. 5. It will be noted that the bent end portion of the plate 3

is disposed some distance radially from the hub 2^a and another plate 3^b similar to the plate 3 is secured to the disc 2^b diametrically opposite to the plate 3 and having its bent 5 end forwardly projecting and disposed much more adjacent the hub 2^a. The plate 3^b is thus at a different radial distance from the center of the disc than the plate 3.

Rotatively supported in pairs on the top 10 of the casing and in small brackets 4 secured to the rear wall thereof are small shafts or rods 5. The rods 5 extend upwardly through a small casing 6 shown as of a substantially rectangular form and 15 supported on the top of casing 1. A spring plate 7 forming a switch contact is supported in casing 6 by a bolt 8 extending through the center thereof and centrally through the rear wall of said casing. A 20 sleeve 9 surrounds the bolt 8 and spaces the spring plate 7 from the wall of the casing, the bolt and sleeve being insulated from the casing by insulating plates at each side thereof, the parts being clamped to the casing by a suitable nut applied to said bolt. The bolt 8 is extended some distance beyond the casing and its threaded end provided with a binding nut 10. Secured in the front wall of the casing 6 are spaced binding posts 25 11 and 11^a having their inner ends disposed adjacent the plate 7 and being clamped to and insulated from the wall of the casing 7. These binding posts are also equipped with suitable binding nuts 12 and 12^a. The 30 shafts 5 extend through the said casing between the plate 7 and the front wall thereof and have secured thereto by clamping nuts threaded thereon cam members 13, adapted, when turned to the dotted position 35 shown in Fig. 3, to press against the ends of this spring plate 7 and flex the same so that said ends are moved into contact with the binding posts 11 and 11^a. The shafts 5 are equipped with lugs 14 and 14^a 40 pinned or otherwise rigidly secured thereto and these lugs are arranged to extend adjacent to the disc 2^b. The lug 14 is so disposed that the projecting end of the same will be in the path of the plate 3 when the same moves to its outward position 45 shown in dotted lines in Fig. 5. While the lug 14^a on the other shaft 5 will be in the path of the plate 3^b when it is disposed in its outward position after being released 50 by the film A. The shafts 5 are also equipped at their upper ends outside the casing 6 with members 15 and pins projecting therefrom by which the shafts can be turned to the desired position.

60 As shown in Fig. 3 members 8, 11 and 11^a are connected in an electrical circuit comprising a battery B, a buzzer D and a 2-pole switch C.

The operation of the device as described 65 is as follows:

The plate 3 will be pushed inwardly between the layers of the film and the point 3^a thereof held in engagement with the apertures in the film to hold the plate in its inward position. The shafts 5 will be 70 disposed as shown in full lines in Fig. 3. The plate 3^b will likewise be pushed inwardly and engage with the film to be held in similar position. As the film A is now 75 unwound and the reel 2 rotated, the layers on the plate 3 will be removed and when the layer immediately above the end of this plate is removed therefrom the plate will spring to its outward position shown in Fig. 5. As the reel 2 rotates, this plate will 80 then come in contact with lug 14 which lug will be turned thereby to turn one of the shafts 5 substantially 90 degrees. This will result in a cam member 13 on said shaft being turned into contact with one end of 85 plate 7 which will be pushed into contact with a binding screw 11. An electrical circuit will now be closed through the circuit as shown in Fig. 3 and the buzzer D or other signaling device used will be actuated 90 to indicate to the operator that the film is nearing its end. The operator will then throw the lever of switch C from the pole shown in contact in Fig. 3 to another pole. As the film continues to unwind and reaches 95 substantially its end portion, the plate 3^b will likewise be released and will be carried into contact with the lug 14^a. The other shaft 5 will then be turned and the lug 13 100 thereon brought into position to bend the other end of plate 7 into contact with the post 11^a. This will again close an electrical circuit through the indicator D and the operator will be informed that the film is at 105 its end. The machine can then be stopped. If desired, the electrical circuits closed by the action of the plates 3 and 3^b can be connected to the operating device to light the 110 projecting lamp on the second machine and also to start the second machine when the 115 film on the first machine is at an end.

Figs. 5 and 6 show a modified form of actuating plate comprising a spring wire bent at its center portion to form a loop or bight 16 the ends of which are bent to project at 115 a right angle and form a projecting portion 16^a. The wire is then formed into two coiled springs 16^b, the ends of which are projected and flattened and suitably secured to the disc 2^b. The plate or disc 2^b is formed with 120 an opening 17 adjacent the member 16. In operation the loop 16 will be bent downwardly and inwardly through a disc 2^b and brought between the layers of the film A as shown in Fig. 5, the projection 16^a being 125 then in vertical position adjacent the disc 2^b as shown in dotted lines in Fig. 5. When the film releases the loop 16 the same will spring to vertical position just outside the disc 2^b and the projection 16^a will project 130

outwardly in position to come in contact with its respective lugs 14 or 14^a.

Fig. 7 illustrates the circuit used when the member 14^a is used to start the auxiliary machine. The conductor from the contact 11^a is then carried direct to the battery B instead of passing through the switch C and signaling device D. A solenoid S is placed in the circuit and is actuated when the circuit is closed by member 14^a to permit the switch T to close. This switch closes the starting circuit for the motor E which drives the auxiliary machine, and this machine is thus placed in operation.

From the above description it is seen that applicant has provided simple and efficient means for indicating to the operator of the motion picture machine just when the film is nearing its end and when the same is substantially at its end. The operation of the machine and the auxiliary machine can then be governed accordingly and if desired, the auxiliary machine can, as stated, be controlled by the said indicating device. The efficiency of this invention has been amply demonstrated in actual practice.

It will, of course, be understood that various changes may be made in the form, details and arrangement of the device without departing from the scope of applicant's invention, which, generally stated, consists in the matter shown and described and set forth in the appended claims.

What is claimed is:

1. In a moving picture machine having a film carrying flanged spool and a casing in which the spool turns, an indicating device comprising a member secured to the flange of said spool adjacent said casing and having a portion projecting through said flange and adapted to be held in position under tension by the film, said member being adapted to move outwardly in a direction toward the spool flange to which it is secured when initially released by the film, means disposed in the path of said member when in such released position, and an alarm device operated by said means.

2. In a moving picture machine having a film carrying flanged spool and a casing in which the spool turns, an indicating device comprising a member secured to the outside of the flange of the spool which is adjacent the casing, said member having an arm extending through an aperture formed in the spool and adapted to be held in position under tension by the film on the spool, said member being adapted to move outwardly away from the flange when released by the film, a member secured to the inside of the casing, a shaft journaled in said member extending between the casing and the spool, a switch disposed on the outside of the casing, a dog member secured to said shaft in position to be contacted by said first mentioned

member when in released position, and a switch operating member secured to said shaft outside of said casing, said switch comprising a flexible member contacted by said latter member for operating the switch.

3. In a moving picture machine having a film carrying spool and a casing in which the spool is disposed, an indicating device comprising a pair of resilient members secured to the flange of the spool at different radial distances from the center thereof adjacent the casing, said members being adapted to spring outwardly away from the flange and film when released by the latter, and adapted to project through said flange and be held in position by the layers of film, a pair of shafts pivoted in said casing, and dog members secured to said shafts adapted to be contacted, respectively, by said first mentioned members when in released position and members secured to the tops of said shafts outside of the casing adapted to operate a switch when the shaft is turned by said dogs.

4. In a moving picture machine having a film carrying flanged spool and a casing in which the spool turns, an indicating device comprising a member secured to the flange of the spool and adapted to be held in position by the layers of the film, said member adapted when released to swing outwardly toward the adjacent side of said casing when initially released by the film, and means disposed in the path of said member when released adapted to actuate an alarm device.

5. In a moving picture machine having a film carrying flanged spool and a casing in which the spool turns, an indicating device comprising a member carried by said spool adjacent said casing and having a portion normally disposed substantially in the plane of the spool flange and having a portion normally projecting through said flange and adapted to be held in position under tension by the film, said member being adapted to swing outwardly toward the adjacent wall of the casing when initially released by the film, means disposed in the path of said member when in such released position, and an alarm device operated by said means.

6. In a moving picture machine having a film carrying flanged spool and a casing in which the spool turns, an indicating device comprising a resilient member secured to said spool having a long arm and a short arm adapted to swing together, one of said arms being normally adapted to project through the flange of the spool and be held in place by the layers of the film, said arms being adapted to move outwardly toward the adjacent wall of the case when released by the film and a dog in the path of said member when in released position adapted to actuate an alarm.

7. In a moving picture machine having a

4

film carrying flanged spool and a casing in which the spool turns, an indicating device comprising a resilient member having two arms, one of which is secured to the flange 5 of said spool and another of which is adapted to project from the flange and be held in place by the layers of the film, the latter mounted to swing outwardly and toward the flange when released by the film and an 10 alarm actuating device adapted to be contacted by said member when in released position.

8. In a moving picture machine having a film carrying spool and a casing in which 15 the spool is disposed, an indicating device comprising a pair of spring members se-

cured to the flange of the spool at different radial distances from the center thereof adjacent the casing, said members having means adapted to swing outwardly away 20 from the flange, and means adapted to project through said flange and be held in position by the layers of film, a pair of shafts pivoted in said casing, and dog members secured to said shafts adapted to be contacted, 25 respectively, by said first mentioned means when in released position and members secured to the tops of said shafts outside of the casing adapted to operate a switch when the shaft is turned by said dogs. 30

In testimony whereof I affix my signature.

VIRGIL C. FRANCIS.
